UNITED STATES PATENT OFFICE.

JOSEPH J. MARESH, OF TERRELL, TEXAS.

PHOTOGRAPHIC-PRINTING MACHINE.

Application filed January 7, 1928. Serial No. 245,207.

This invention relates to a photographic printing machine, and has for its object to provide, in a manner as hereinafter set forth, a machine of such class which will print 5 both a photographic view and a border for the latter without manually handling or adjusting the surface upon which the photographic print is made for the reception of the border.

10 A further object of the invention is to provide, in a manner as hereinafter set forth, a machine for the purpose referred to including means for automatically retaining a photographic print in position to have a 15 border applied thereto.

Further objects of the invention are to provide, in a manner as hereinafter set forth, a photographic printing machine which is simple in its construction and arrangement, 20 strong, durable, compact, automatic in its action, expeditiously printing a photographic view surrounded by a border, readily assembled, and comparatively inexpensive to set up.

25 With the foregoing and other objects in view the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the 30 scope of the claims hereunto appended.

35 In the drawings wherein like reference characters denote corresponding parts throughout the several views:

Figure 1 is a perspective view of a photographic printing machine in accordance with 40 this invention.

Figure 2 is a sectional plan.

Figure 3 is a vertical sectional view thereof.

Referring to the drawings in detail a 45 photographic printing machine in accordance with this invention comprises an open bottom housing including a front wall 1, a pair of side walls 2, 3, an inclined top 4 the inclination being downwardly from rear to front and a rear wall 5, which is of greater length than the front wall 1. The top wall 4 has its rear portion 6 of greater length than its forward portion 7. Vertical wall forming members 8 are secured to the front 50 and ends of the rear portion 6 of the top wall. One of said wall forming members 8 is spaced from the side wall 3 of the housing. The setting up of the housing in the manner referred to provides the housing of T-shaped contour whereby the rear portion 60 thereof is of greater width than the forward portion. The top wall 4 in the portion 7 thereof is provided with an opening 9 and in the portion 6 thereof with an opening 10. Secured to the inner faces of the side walls 65 2, 3, below the portion 7 of the top wall 4, and also abutting against said portion 7 is a pair of uprights 11, 12 of less height than the height of the walls 2, 3. The uprights 11, 12 are arranged below the rear part of 70 the portion 7 of the top wall 4. Secured to the lower ends of the uprights 11, 12, is a transversely extending flat member 13. Arranged between the uprights 11, 12 as well as depending below the member 13 is a pair 75 of spaced partitions 14, 15, which extend from the top wall 4 to the bottom of the side walls 2, 3. The partition 14 is inclined rearwardly from its upper towards its lower end. The partitions 14, 15 abut against the 80 inner faces of the side walls 2, 3 below the member 13. The uprights 11, 12 in connection with the member 13 and partitions 14, 15 form a reflector chamber 16 which has its top closed by a ground glass 16' positioned at the rear of the opening 9. The partition 15 includes a perpendicular lower portion 17 and an offset upper portion 18 which is disposed rearwardly with respect to the portion 14 and the latter in proximity 85 to the member 13 is provided with a light entrance opening 19. Secured to the partition 14 and arranged upon the bottom member 13 is a support 20 for an inclined reflector 21 and with the inclination of the latter being forwardly from its bottom to its top or in other words the reflector 21 inclines from the partition 15 to the partition 14. The reflector 21 has its upper portion seated on the support 20 and its lower edge arranged at the corner between the member 13 and the portion 17 of the partition 15. 90

The partition 14 in connection with the front wall 1 provides a lamp compartment 100 22 having an open top arranged at the forward part of opening 9. The partition 15 in connection with the rear wall 5 provides a compartment 22 for the purpose to be presently referred to. Secured to the partition 14 and extending forwardly from the lower portion thereof is a support 24 for a 105 110

lamp 25. Secured to the lower portion of the partition 15 and extending rearwardly therefrom is a support 26 for a lamp 27 which is positioned at the opening 19 and 5 opposes the reflector 21. Arranged at the rear of the compartment 23 and supported from the inner face of the rear wall 5 is a vertically disposed valve casing 28, formed with a diagonally disposed partition 29 provided with an opening 30. Positioned 10 within the casing 28 and arranged above the partition 29 is a hinged valve 31 which is employed for closing the opening 30. When the valve 31 is shifted to closing position 15 with respect to the opening 31, the latter establishes communication between the compartments 32, 33 provided in the casing 28 by the partition 29. The valve 31 is hinged as at 34 to the forward wall or casing 20 28 and is normally disposed at an inclination and against the partition 29 for the purpose of closing the opening 31. The forward wall of the casing 28, near its upper end is provided with a slot 35 for a purpose 25 to be presently referred to. The casing 28 is arranged below the opening 10 in the rear portion 6 of the top wall 4 of the housing and is formed in its upper end with an opening 36 into which is secured a flexible 30 suction pipe 37 which extends through the opening 10. Connected to the bottom of the casing 28 and communicating with the latter is an outlet pipe 38 which opens into a motor driven suction device 39 which is arranged 35 below the bottom of the housing and supported by a cross member 40 which is secured to a pair of spaced, vertically disposed supporting standards for the rear of the housing. A front supporting standard 42 is 40 employed for supporting the reduced front portion of the housing. The standard 42 is connected to one of the standards 41 by a pair of angularly disposed base members 43. Secured to the rear wall 5 is a plug 44 for 45 the leading in wires 45, 46 which extend from a suitable electrical source. Extending from the socket 47, which associates with the plug 44, are circuit connections 48, 49 which lead to an outlet box 50 secured to the side wall 2 within the compartment 23. Leading 50 from the outlet box 50 to a contact member 51 is a circuit connection 52. Associated with the contact 51 is a contact member 53 and leading therefrom to the motor of the suction device 39 is a circuit connection 54. Leading from the motor of the suction device 39 to the outlet box 50 is a circuit connection 55. The circuit connections 52, 54 and 55 in connection with the contacts 51, 56 55 provide the motor circuit. Leading from the outlet box 50 to the binding posts 56, 57 are circuit connections 58, 59 respectively. Leading from the binding posts 56, 57 to the contact members 60, 61 are circuit connections 62, 63 respectively. The circuit con- 60 nections 58, 59 binding posts 56, 57, circuit connections 62, 63 and contacts 60, 61 provide the circuit for the lamp 27. Leading from the outlet box 50 to a contact member 66 to a binding post 67 is a circuit connection 68. 70 Leading from a binding post 69 to the outlet box 50 is a circuit connection 70. The contacts 64, 66, binding posts 67, 69 and circuit connections 65, 68 and 70 provide the circuit for the lamp 25. The circuit for the lamp 75 25 is normally open, and the circuit of the lamp 27 is normally open. The circuit of the motor of the suction device is normally open. The contacts 51, 53 are normally spaced from each other. The contacts 60, 61 are normally spaced from each other. The contacts 64, 66 are normally spaced from each other. The contact 51 is shifted, in the manner as hereinafter set forth, to engage the contact 53 to close the motor circuit. 80 The contact 61 is shifted to engage the contact 60 in the manner as hereinafter set forth to close the circuit of the lamp 27, and the contact 64 is shifted to engage the contact 66 in the manner as hereinafter set forth for 90 the purpose of closing the circuit of the lamp 25. Secured to the portion 6 of the top wall 4 is a pair of spaced supports or brackets 71, 72, having a shaft 73 pivotally mounted 95 therein and arranged therebetween. Carried by the shaft 73 is a pair of spaced arms 74 which are fixedly secured to the sides of a printing head indicated generally at 75 and which consists of a hollow casing 76 formed with side and end walls and a top and bottom and with the latter provided with a series of openings 76' which register with openings 77 formed in a flexible member 78 which is secured to the lower face of the bottom of the head of the casing 76. The flexible suction pipe 37 is connected to the rear of the casing 76 and communicates therewith. 100 The printing head 75 is arranged over the chamber 16 and is employed for maintaining the object such as a sensitized sheet of paper in position to be printed, and is further employed for retaining the printed object in an elevated position relative to the upper end of the chamber 16. The head 75 is normally in an elevated position and disposed at an inclination, in a manner as shown in Figures 1 and 3. Connected with one of the arms 74 is a manually operated 110 spring controlled shifting mechanism for the head. The said mechanism includes a shiftable member formed of an upper section 79 and a lower section 80 normally arranged in superposed spaced relation and with the lower end of the section 79 opposing the upper end of the section 80. Each of said sections is in the form of a bar of rectangular cross section. The section 80 carries a sleeve 81 at its upper end into which extends 115 120 125 130

the lower end of the section 79, and the latter is cut away at its forward edge to provide a shoulder 82 which overlaps the top edge of the sleeve 81 and is adapted to abut against 5 the same on the downward shift of the section 80. The contact member 60 is carried on one side of the lower end of the section 79 and the contact member 61 is carried on one side of the upper portion of the section 10 80. The contact members 60, 61 are of hook-shaped contour and not only act to close the circuit for the lamp 27, but further act to couple the sections 79 and 80 together whereby on the downward movement of the section 15 80, the contact member 61 will overlap and engage the contact member 60 and carry the section 79 downwardly with the section 80. The shoulder 82 abuts against the sleeve 81 when the shifting member for the head 20 75 moves downwardly. The section 80 is pivotally connected at its lower end, as at 83 in the bifurcated inner end 84 of a pivoted foot tread 85. The tread 85 is pivotally connected to one of the base members 43. 25 Connected to the support 26 and also to the inner end of the foot tread 85 is a controlling spring 86 for the shifting mechanism for the head 75 and said spring 86 normally acts to maintain the head 75 in an elevated position, 30 and the lowering of said head 75 is had against the action of the spring 86. The operation of the shifting mechanism for the head 75 is to shift the same to holding position with respect to the object to be printed 35 on, and closes the circuit for the lamp 27.

The circuit for the motor of the suction device is closed on the shifting of a spring controlled lever 87 which carries the contact member 51. The lever 87 also acts as 40 means for shifting the valve 31 from closing position with respect to the opening 30 and for such purpose the valve 31 is provided with a pull bar 88, which extends through the opening 35 and is pivotally attached, as at 89 to one end of the lever 87. The pivot 90 for the lever 87 is eccentrically disposed with respect thereto and is positioned between the transverse median and the outer end of the lever 87. The pivot 90 45 for the lever 87 is carried by a support 91 which is secured to the inner face of the side wall 3 at the rear thereof. A controlling spring for the lever 87 is indicated at 92 and which is attached at one end to the outer end of the lever 87 and at its other end attached to the upright 12. The lever 87 has its outer end shifted inwardly, for the purpose of bringing the contact member 51 into engagement with the contact 53, 50 and also for the purpose of shifting the valve 31 from closing position with respect to the opening 30, by a push bar 93 which is attached to the outer end of the lever 87 and passes through a slot or channel 93 provided in the upright 12. The push bar 92

extends through an opening 94 formed in the front wall 1. The outer end of the push bar 93 carries a knob 95 positioned a substantial distance from the outer face of the wall 1.

Positioned over the portion 7 of the top wall 4 and extending upon the portion 6 thereof, is a pair of spaced, parallel guide rods 96 having the inner ends anchored in brackets 97 and the outer ends secured to 70 brackets 97'. The brackets constitute stops for a bridge 99 and are fixed to the wall 4. The rods 96 in connection with the brackets 97, 97' provide a combined guide and stop element for the bridge 99 which is slidably 75 mounted on the rods 96 and is manually shifted. The bridge 99 consists of a frame 99' carrying a clear glass 99''. Extending laterally from each side of the frame 99' is a front and rear sleeve 96', 96'' slidably 80 mounted on a bar 96. The sleeves 96' are adapted to abut the brackets 97' to limit the outward movement of the bridge 99 and the sleeves 96'' coat with the brackets 97 to limit the inward movement of the bridge. 85

Detachably connected with the frame 99' of the bridge 99 is a combined mask and border 100 which extends over the rear portion of the glass 99''. There will be employed a different mask and border 100 for 90 each size roll, cut film and plate, which is the negative. Studs 100' are carried by sides of the frame 99' for engagement with extensions 100'' on the combined mask and border 100 to retain the latter in position. 100 Hinged to the outer end of the frame 99', is a mask 101 for positioning over the forward portion of the glass 99''. The hinge connection between the mask 101 and frame 99' is indicated at 102. The portion 6 of 105 the top wall 4 is provided with an opening 102' normally closed by a removable cover member 103. The opening 102' provides means whereby access can be had to the chamber 23 to remove and replace a lamp. 110 The bridge 99 has a depending pin 104 capable of engaging with the contact member 64 for the purpose of shifting it to engage the contact member 66 whereby the circuit for the lamp 25 is closed.

The negative is adapted to be positioned under the mask 101, and upon the mask is arranged the object printed on, such as a sheet of paper or other suitable material. After the paper has been positioned on the 115 mask, the bridge 99 is moved inwardly to position the negative over the top of the compartment 16. When the negative and paper are being positioned, the circuit for the lamp 25 is closed so that the operator 120 can ascertain that the negative and paper are being properly positioned. After the negative has been arranged at the top of the chamber 16, the operator applies pressure to the foot tread 85 which closes the 125 130

lamp circuit 27 and the light rays passing through the opening 19 will be deflected upwardly by the reflector 21. When the circuit for the lamp 27 is closed, the printing head 75 will be moved downwardly so that the flexible member will engage the paper and hold the same in position while it is being printed. When the head 75 engages the paper the operator then pushes the rod 92 inwardly which closes the motor circuit and shifts the valve 31 so that communication is established between the compartments 32 and 33. On the close of the motor circuit the suction device will be operated 10 causing a vacuum in the head 75 whereby the object or paper which has been printed upon will be permanently retained against the member 76'. Pressure on the foot tread 25 is then released, but the rod 92 is held in 15 its inward position, so that the suction device will be still operating. The bridge is then moved downwardly to position the mask and border 100 over the top of the compartment 16, the operator then applies 20 pressure to the foot tread 85 which moves the head 75 downwardly, carrying the object which has been printed to a position over the mask and border 100 and the printed photograph will then have applied 25 thereto a border surrounding the same. The operation is carried on without adjusting the paper or object printed until after the border has been applied, or in other words 30 after the object to be printed on, or the sensitized paper has been positioned on the mask 101 it is not handled until the border has been applied thereto. When the operation 35 of the suction device has been discontinued by pulling the bar 92 outwardly, the printed picture surrounded by the border 40 can be conveniently moved from the head 75.

It is thought the many advantages of a photographic printing machine, in accordance with this invention, can be readily understood, and although the preferred embodiment of the invention is as illustrated and described, yet it is to be understood that changes in the details of construction 45 can be had which fall within the scope of the invention as claimed.

What I claim is:

1. In a photographic printing machine, a source of light, a slidable bridge adapted to 55 carry a sensitized object to be photographically printed, said bridge including a negative retaining means and a border applying means providing for respectively positioning the negative and border applying means 60 relative to said source, a shiftable printing head arranged over the bridge for retaining the object in position relative to the negative during the printing from the latter on the object, a suction means cooperating with 65 the head to retain the printed object on the

latter when the bridge is shifted to position the border applying means relative to said source, and means for lowering said head to engage the object to hold the latter relative to the negative and when the head carries the object to hold the latter relative to the border applying means. 70

2. In a photographic printing machine, a source of light normally in an open circuit, a slidable bridge adapted to carry a sensitized object to be photographically printed, said bridge including a negative retaining means and a border applying means and providing for respectively positioning the negative and border applying means relative to said source, a shiftable printing head arranged over the bridge for retaining the object in position relative to the negative during the printing from the latter on the object, an electrically operated suction 80 means cooperating with the head to retain the printed object on the latter when the bridge is shifted to position the border applying means relative to said source, and spring controlled means for lowering said head to engage the object to hold the latter relative to the negative and when the head carries the object to hold the latter relative to the border applying means, said spring controlled means including a circuit opening and closing device for said light source for closing the circuit of the latter when said head is lowered, and means for controlling the operation of said suction device. 90

3. In a machine for photographically printing a bordered picture a slidable element for carrying a sensitized object to be photographically printed and including a negative retaining means and a border applying means, said element providing for 100 respectively positioning the negative and border applying means relative to a source of light, a printing head for retaining the object in position to have the picture printed thereon when said element is shifted to 110 position the negative relative to the light source, suction means cooperating with said head for detachably securing the object thereto when said element is shifted to position the border applying means relative to the light source, and means for shifting said head to object retaining position and to position the object to have the border applied thereon. 115

4. In a machine for photographically printing a bordered picture a light source, a slidable element for carrying a sensitized object to be photographically printed and including a negative retaining means and a border applying means, said element providing for respectively positioning the negative and border applying means relative to said light source, said light source normally in an open circuit, a printing head for retaining the object in position to have the 120 125 130

- picture printed thereon when said element is shifted to position the negative relative to the light source, suction means cooperating with said head for detachably securing the object thereto when said element is shifted to position the border applying means relative to said light source, and spring controlled means for shifting said head to object retaining position and to position the object to have the border applied thereto, said spring controlled means including circuit opening and closing means for said light source moved into active position when said head is shifted to object retaining position and to position the object to receive the border, and controlling means for said suction device.
5. In a machine for photographically printing a bordered picture, means for successively photographically printing the picture and border upon a sensitized object including a light source and a shiftable element for successively positioning a negative and a border applying means relative to the light source, said element further including a carrier for positioning the object to be printed from the negative, and a shiftable printing head for successively retaining the object in position to have the picture and border printed thereon, and means coacting with said head for detachably securing said object thereto after being printed with the picture when the negative is shifted from and the border applying means is shifted to active position with the light source.
6. In a machine for photographically printing a bordered picture, means for successively photographically printing the picture and border upon a sensitized object including a light source and a shiftable element for successively positioning a negative and a border applying means relative to the light source, said element further including a carrier for positioning the object to be printed from the negative, a shiftable printing head for successively retaining the object in position to have the picture and border printed thereon, means coacting with said head for detachably securing said object thereto after being printed with the picture when the negative is shifted from and the border applying means is shifted to active position with the light source, controlling means for the light source, and controlling means for the means coacting with the head for detachably securing said object thereto.
7. In a machine for photographically printing a bordered picture, means for successively photographically printing the picture and border upon a sensitized object including a light source and a shiftable element for successively positioning a negative and a border applying means relative to the light source, said element further including a carrier for positioning the object to be printed from the negative, a shiftable printing head for successively retaining the object in position to have the picture and border printed thereon, means coacting with said head for detachably securing said object thereto after being printed with the picture when the negative is shifted from and the border applying means is shifted to active position with the light source, a spring controlled actuating means for said head, said spring controlled actuating means carrying controlling means for said light source, and means for controlling the means coacting with the head for detachably securing the object thereto.
8. In a machine for photographically printing a bordered picture, means for successively photographically printing the picture and border upon a sensitized object including a light source and a shiftable element for successively positioning a negative and a border applying means relative to the light source, said element further including a carrier for positioning the object to be printed from the negative, a shiftable printing head for successively retaining the object in position to have the picture and border printed thereon, means coacting with said head for detachably securing said object thereto after being printed with the picture when the negative is shifted from and the border applying means is shifted to active position with the light source, spring controlled actuating means for said head, said spring controlled actuating means carrying controlling means for said light source, the said means coacting with the head and including an electrically operated suction device, and controlling means for said device.

In testimony whereof, I affix my signature hereto.

JOSEPH J. MARESH.
